F. H. SCHLODTMANN

ELEVATING FOOTSTOOL

Filed Dec. 29, 1926

Patented June 19, 1928.

1,674,180

UNITED STATES PATENT OFFICE.

FREDERICK H. SCHLODTMANN, OF BROOKLYN, NEW YORK.

ELEVATING FOOTSTOOL.

Application filed December 29, 1926. Serial No. 157,683.

The present invention broadly relates to improvement in foot-stools and more particularly in foot-stools which are adapted to assume either an elevated or a lowered position.

Among the principal objects which the invention has in view are: To provide novel means for raising and lowering the foot-stool; to provide, in connection with the foot-stool, a foot rest which is adapted to be exposed in service position when the foot-stool is elevated and concealed when the foot-stool is lowered; to provide a novel construction of footrest, so designed that it may turn to various positions to accommodate the foot of the user; and generally to provide improvements in foot-stools with a view to simplifying and cheapening the construction and rendering the same efficient and reliable in service.

With these and other objects in view, the invention further resides in the details of construction and arrangements of parts more specifically described and pointed out in the following description of the accompanying drawing forming a part of this specification.

In the drawings:—

Figure 1 is a perspective view of a foot-stool constructed in accordance with the invention and showing the same in elevated position with the footrest exposed and disposed in service;

Figure 2 is an end elevational view of the foot-stool in its lowered position;

Figure 3 is a sectional view in elevation on the line 3—3 of Figure 2 showing the way in which the footrest is concealed; and

Figure 4 is a fragmental sectional view in elevation of the footrest preferably employed.

Referring now to the drawings in which like reference numerals denote like parts throughout the various views, the invention is embodied in a foot-stool, preferably constructed of wood, and which comprises a stationary portion and a portion which is adapted to be elevated with respect thereto.

The stationary portion consists of two frames, 10 and 11, preferably rectangular in shape and composed of narrow boards rigidly fastened together in any suitable manner. The frames are disposed in parallel, vertical alignment and are securely maintained in position by brace members such as relatively wide boards, 12 and 13, arranged verti-

cally on opposite sides of the foot-stool and vertical corner boards, 14 and 15. All of these boards are fastened to the frames, 10 and 11 and with the frames form the skeleton of the foot-stool. The ends of the boards comprising the bottom frame, 11, overlap the edges to augment the stability of the structure and may be finished off in some fancy manner like that shown best in Figure 1, to render the foot-stool more pleasing in appearance. A rather wide board, 16, forms a part of the top of the foot-stool and is attached to the top of the frame, 10, and covers approximately one-half the area thereof. A number of thin pieces of wood, 17, extend across the bottom of the frame, 11, forming in effect a shelf on which articles such as a bootblack's implements of trade may be laid and carried with the foot-stool.

The elevating portion of the foot-stool includes two vertical oppositely disposed boards, 18 and 19, to which is attached a horizontal board, 20, forming the other part of the top of the foot-stool. The vertical boards are adapted for sliding vertical movement between the vertical members, 12 and 14, and 13 and 15, and are guided between the frame, 10, and transverse members, 21 and 22, which are secured to the frame, 10. To the bottom of each vertically movable board are hinged folding members, 23 and 24, shown as boards, of the same width as the boards, 18 and 19. When the foot-stool is lowered they are folded vertically on the boards, 18 and 19, as best seen in Figure 3, and, when the foot-stool is elevated, they are swung downward to form a continuation of the boards, 18 and 19, as shown in Figure 1, and to hold the latter in elevated position. Means in the form of thumb-catches, 25, pivoted to the brace members, 12 and 13, serve to maintain the folding boards in position when the foot-stool is elevated and prevent them from swinging on their hinges to cause the collapse of the foot-stool. In order to further insure against the collapse of the foot-stool, the transverse members, 21 and 22, may be provided with perforations, 26 and 27, which, when the foot-stool is in its elevated position, align with perforations 28 and 29, in the boards, 18 and 19. Pins, 30, are adapted to be inserted in the aligning perforations to hold the boards, 18 and 19, securely in position. In order to prevent the pins from

100

105

110

becoming lost or mislaid they may be fastened to the foot-stool as by chains, 31 (and when the foot-stool is lowered they may be shoved in holes provided for the purpose).
5 When the foot-stool is in its lowered position, the folding members, 23 and 24, are held in folded position by means such as spring catches, 32, which, however, may be easily disengaged to allow the folding members to be released and the foot-stool elevated.

10 The foot-stool is provided with a footrest, 33, which is attached to a base member, 34, such as a flat board. This base member is hinged to the inner edge of the top, 20, of the elevating portion of the foot-stool in the manner best seen in Figure 1. When the foot-stool is not in use and in its lowered position, the footrest assumes the concealed position shown in Figure 3, having been swung on its hinges to this position prior to the lowering of the stool. When the footstool is elevated, the footrest is swung to the exposed position seen in Figure 1 where it is disposed for service. In this position the base member covers a hand hole, 35, which may extend through the top, 20, and is for the purpose of enabling the foot-stool to be conveniently carried around when in its lowered position.

15 The construction of the footrest is best shown in Figure 4. It comprises the customary footform, 36, supported by the member, 37. The footform and the member, 37, are pivotally attached to the base, 33, as by the bolt 38. The nut of the bolt is concealed in a well formed in the footform. This bolt may be either secured in such manner as to rotate with the footrest, or the footrest may 20 rotate with respect to the bolt. In order to provide for an easy rotation of the footrest, means such as ball bearings, 39, may be employed. These ball bearings are preferably sunk in holes in the member 37, and bear 25 against the heads of screws, 40. The screws serve a dual purpose. They serve to secure the footform to the member, 37, and they provide an adjustment for the footrest, for,

30 by varying the positions of the screws, or by using screws of different sizes, different elevations of the footrest will result. The ball bearings rest on a flat metallic plate, 41, attached to the base member, 33, which plate is employed to prevent the ball bearings from forming ridges in the base member, 41. The 35 rotatable character of the footrest permits it to be readily turned to the position which best suits the foot of the user.

35 While I have disclosed the invention as embodied in a footstool, it will be understood that it may be used for a wide variety of purposes. For example, it serves as an admirable step ladder, which may be used by store keepers and others to enable them to reach articles at an elevated position. It is 40 also susceptible of other uses which will be apparent.

45 The above description is to be construed merely as illustrative and not in a limiting sense for numerous variations may be made 50 in the specific constructions described without departing from the spirit of the invention or the scope of appended claims.

55 What I claim is:

1. A device of the class described comprising a frame, a horizontal member attached to the top of the frame, and another horizontal member vertically movable relative to the frame, said member in its lower position being disposed in the same plane as the first horizontal member and forming a continuation thereof.

2. A device of the class described comprising a frame, a horizontal member attached to the top of the frame, and another horizontal member having collapsible legs adapted to maintain said member in an elevated or a lowered position, said member in its lowered position being disposed in the same plane as the first horizontal member and forming a continuation thereof.

60 In testimony whereof, I have signed my name to this specification this 26th day of December, 1926.

FREDERICK H. SCHLODTMANN.
